Primary Examiner — Prabhakar Deshmukh(74) *Attorney, Agent, or Firm* — Panitch Schwarze Belisario & Nadel LLP(57) **CLAIM**

The ornamental design for a jukebox, as shown and described.

DESCRIPTION

FIG. 1 is a front perspective view of a jukebox showing our new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken lines in the figures are for the purpose of showing environmental structure, are for illustrative purposes only, and form no part of the claimed design.

The rear elevational view of the jukebox is not shown in the drawings or described in the specification and, therefore, forms no part of the claimed design.
